Application February 12, 1957, Serial No. 639,675

Claims priority, application Japan May 16, 1956

2 Claims. (Cl. 18—8)

This invention relates to devices for producing synthetic yarn, and more particularly to devices for producing yarn having thin portions and thick portions.

In conventional apparatus for producing rayon yarn of the above-noted type, a spinning pump and a plunger pump are generally arranged in parallel and thin portions of yarn are formed from liquor supplied by the spinning pump and thick portions of yarn are formed by adding liquor supplied by the plunger pump. However, in this operation, the mean size and the ratio of the sizes of the thin portions and thick portions are greatly varied, and due to this fact, it is necessary to stop the operation from time to time in order to adjust the feeding of the liquor by the plunger and to adjust the ratio of the sizes. It is evident that these adjustments decrease the efficiency of the operation and the yields thereof.

In order to eliminate the disadvantages as described above, a spinning pump and a plunger-type amplitude device are arranged in accordance with the invention in series, and liquor is fed to the amplitude device and the liquor is spun to form thick and thin portions under the control of the amplitude device. More particularly, the liquor is passed to the amplitude device by an ordinary spinning pump and the thin portions of the yarn are formed, for example, by an outlet valve maintained slightly open while the thick portions of the yarn are formed with liquor which is fed intermittently to the outlet valve by the reciprocating motion of the plunger of the amplitude device. Preferably, the inlet of the amplitude device has no valve and is directly connected to the spinning pump, but a control valve (e.g. a ball valve, a needle valve, a flat valve, or the like) is provided at the outlet and supported by a spring in such a way that the spring is compressed by the pressure of the liquor to maintain the valve in a slightly open condition in order to prevent the yarn from breaking.

The accompanying drawing illustrates a preferred embodiment of the invention in order to facilitate the understanding thereof, but it is to be understood that the invention is not limited to the embodiment shown in the drawing, since it is evident that the embodiment may be altered in many ways without departing from the spirit and the scope of the invention.

In the drawings:

Figure 1 is a front view, shown partly in section, of one of the embodiments of the invention, and

Figure 2 is a side view, shown partly in section along line II—II of Fig. 1, of the same apparatus.

In the drawing, a spinning pump or supply device 2 which is adapted to feed liquor at a constant predetermined rate (for example, a gear pump) is mounted on a pump base 1 and is driven by means of a gear 4 fixed on a driving shaft 3.

Liquor for the yarn is passed through a delivery channel or coupling pipe 5 to a cylinder chamber b in the direction shown by the arrow a when the spinning pump 2

2

is driven. The liquor then acts to operate the outlet valve 6 of an amplitude device 15 and passes into an end base 7 through a pipe c and is ejected from a jet or extrusion device 9 for the spinning operation.

- 5 A plunger-type amplitude device 15 for forming thick portions of yarn is provided, as shown in Figure 2, with a plunger 22 which is adjustably mounted on the top of a lever 17 by an adjustment screw 25. The head of the plunger 22 is set in a ball-shape dish 11 in member 12
- 10 forming the head of the lever 17. A pin 13 connects lower arm 14 of the amplitude device 15 rotatably to lever 17 and a spring 24 connects the lever 17 and the arm 14 to pull the lever 17 towards the arm 14 as shown in the drawing. When the lever 17 is pulled in by the spring 24, the lever 17 comes into contact with a stopper 16. The stopper comprises an eccentric cam 16' which is adjustably mounted on a frame 26 by means of a screw 27. Accordingly the position of the front end of the stopper 16 and consequently the magnitude of the stroke 20 of the lever 17 may be minutely adjusted by turning the cam 16', and thus the amount of the liquor pushed forward by the stroke of the plunger may be accurately controlled. A line shaft 18 is provided with a disc 20 on which a plurality of pins 19 are fixed in any desired relation. When the disc is rotated in the direction of the arrow, as shown in Figure 2, the pin 19 comes into engagement with the lower end of the lever 17 to turn said lever in counter-clockwise direction against the force of the spring 24. Thus, the lever 17 is oscillated intermittently at any desired interval to move the plunger 22 to draw in liquid or to push the liquid out of the cylinder chamber b to the jet 9, thus opening further the slightly open valve 6 to feed the liquor for forming the thick portions of the yarn intermittently.
- 30 35 The valve 6 is supported by a spring 28 which is pressed downwardly by a screw 29, and therefore the force of the valve 6 against the liquor pressure may be adjusted by turning the screw 29. When a pin 19 loses contact with the lever 17, the forward pushing operation of the plunger 22 is stopped and the lever 17 returns to its original position under the action of the spring 24 to contact stopper 16. The forward pushing operation of the plunger 22 is repeated when the next pin 19 comes into contact with the lever 17.
- 40 45 The operation described above may be carried out at any desired intervals whether equal or unequal. For this purpose, the intervals between the pins 19 may be made uniform or different from one another.
- 50 The pushing delivery of the additional liquor is carried out by the reciprocating motion of the plunger 22 as described above. When the plunger 22, however, is moving backward, the liquor may tend to flow in a reverse direction. If such a flow occurs, the feeding of the liquor through the jet 9 may be stopped or decreased to such an extent as to cause the breaking of the yarn. In order to prevent this, the chamber of the valve 6 and the cylinder chamber are directly communicated with the spinning pump 2 so that these chambers will be continuously fed with the liquor and a forward flow of the liquor in an adequate amount through the valve 6 always maintained.
- 55 60 In the apparatus of this invention as described above, it will be noted that the liquor may be pushed forward in order to supply additional liquor for forming thick portions of the yarn by actuating the valve 6 by the plunger intermittently, while a constant feeding of the liquor for forming the thin portions of the yarn is maintained. It will be further noted that the adjustment of the thick portions of the yarn may be achieved by turning of the cam 16' of the stopper 16 to adjust minutely the range of the return stroke of the lever 17 and consequently the stroke of the plunger 22 thereby adjusting

the pulsed supply of the feeding of the liquor. Thus, the ratio of the sizes between the thick portions and the thin portions of the yarn may be varied. It will be also noted that the mean size of the yarn is always maintained by the arrangement of the spinning pump and the plunger type amplitude device in series. It can be easily understood by those experienced in the art that the apparatus of this invention provides various advantages as described above in the production of special rayon yarn such as slub yarn.

It is to be understood that the embodiments may be varied and modified without departing from the scope and the spirit of this invention. For example, while the explanations have been made in the above with reference to the embodiment in which a plunger pump is employed, a pump of another type may be used.

What is claimed is:

1. Apparatus for the production of thread of variable denier from a liquid comprising supply means for supplying the liquid under pressure, an extrusion device, coupling means coupling the supply means and the extrusion device and defining a delivery channel therebetween, pressure varying means coupled to the delivery channel between the supply means and the extrusion device for alternately increasing and decreasing the pressure of 20

5
10
15

the liquid therein, and a liquid supply control device coupled to the delivery channel to maintain a supply of the liquid to the extrusion device, despite the operation of the pressure varying means, to maintain the continuity of the thread, the liquid supply control device comprising a valve in said delivery channel for controlling the flow of liquid therethrough and a spring loading said valve and exerting a force thereupon to allow a flow of fluid through the delivery channel with the pressure varying means reducing the pressure therein.

2. Apparatus as claimed in claim 1 wherein the pressure varying means includes a cylinder opening into the delivery channel, a reciprocating piston in the cylinder, a fulcrumed lever pivoted to the piston, an adjustable cam fixed relative to the cylinder, a resilient device urging the lever into contact with said cam, and a rotary disc including pins for sequentially lifting the lever away from the cam to move said piston, said cam limiting the return movement of the piston.
